UNITED STATES PATENT OFFICE.

WILLIAM F. LOYD, OF CANAL DOVER, OHIO.

FIRE-ESCAPE AND FIREMAN'S LADDER.

SPECIFICATION forming part of Letters Patent No. 476,885, dated June 14, 1892.

Application filed December 4, 1891. Serial No. 414,031. (No model.)

To all whom it may concern:

Be it known that I, WILLIAM F. LOYD, of Canal Dover, in the county of Tuscarawas and State of Ohio, have invented certain new and useful Improvements in Fire-Escapes and Firemen's Ladders; and I do hereby declare the following to be a full, clear, and exact description of the invention, such as will enable others skilled in the art to which it pertains

10 to make and use the same.

My invention relates to improvements in fire-escapes, and more especially to a combined fire-escape and fireman's ladder adapted to be permanently applied to the side of a building; 15 and it consists in certain features of construction and in combination of parts hereinafter described, and pointed out in the claims.

In the accompanying drawings, Figure 1 is a perspective view of a building provided with 20 my improved fire-escape and fireman's ladder. Fig. 2 is a perspective view of the upper portion of the fire-escape. Fig. 3 is a side elevation of the lower portion of the same; and Fig. 4 is a transverse section looking downward, a 25 portion being broken away in Fig. 2 to more clearly show the construction.

A represents a building that near the cornice or eave is provided with a fixed rail B.

My improved fire-escape comprises an upper supporting-frame parallel with the side of the building, C representing the longitudinal or upright members of the frame. Members C at either side of the frame are connected top and bottom by cross-pieces C' and intermediate by one or more cross-pieces, as at C². Members C are also braced, as at C³. Cross-pieces C' afford bearing, respectively, for a shaft or spindle D. Spindles D have mounted thereon at either end, preferably, a sprocket-wheel E, the wheels on one shaft or spindle being connected with the respective wheel on the other spindle or shaft by an endless chain F, and chains F are connected by rounds G, thus constituting an endless ladder, the 45 rounds being secured in any suitable manner. The supporting-frame at the rear and above the windows in the uppermost story of the building is provided with a trolley or traveler H, that is adapted to travel on track B. Members C at the rear side of the supporting-frame have, respectively, between the different stories of the building a rearwardly-projecting

member I, provided with a roller I', that is adapted to travel in contact with the side of the building as the device is moved from one place to another by means of trolley or traveler H. With such construction any unsteadiness or swaying of the device is prevented, and, except in buildings of uncommon height, the device can be moved with great facility 60 from one place to another along the building. Members C of the supporting-frame, it will be observed, inclose the endless chains on three sides—front, rear, and outer side—as shown more clearly in Fig. 4, being preferably made 65 of channel-iron, by which construction the endless chain is prevented from swaying in either direction.

By means of the endless ladder the device may be ascended or descended on the front or 70 rear side, as desired. It is intended, however, that occupants of the building descend on the side adjacent to the building, and hence the device should be located about eighteen inches from the building, the opposite or front side 75 being more especially intended for the use of firemen in getting to or from the roof of the building.

Some suitable means is preferably provided for locking the ladder—that is, preventing it 80 from moving in either direction—and to this end shaft or spindle D at the lower end of the device, and preferably just outside cross-piece C', has rigidly mounted thereon ratchet-wheels K K', cross-piece C' being provided with pawls 85 L L' for engaging the respective ratchet-wheels. Said spindles should also be provided with a crank, as at M, by manipulating which motion may be communicated to the endless ladder when the pawls aforesaid are disengaged from the respective ratchet-wheels, and hence the ladder should extend sufficiently 90 near the ground, so that the crank M will be within convenient reach from the ground or from a chair placed on the ground. 95

On buildings of considerable height, where it would be difficult to push the device by hand from one place to another, I provide a rope or cable, as at R, adapted to wind upon a drum or windlass W, located near a lower 100 corner of the building within convenient access from the ground, the rope or cable thence leading over pulleys P, as shown, and connecting with the supporting-frame of the de-

vice, as at R', with the arrangement such that, according as the windlass or drum is rotated in the one direction or the other, the device will be moved in the direction desired along the side of the building.

Although I have shown rail B for trolley or traveler H on but one side of the building, it is evident that the same can be extended around the building, if desired.

It will readily be observed that my improved device not only possesses all the requirements of a fireman's ladder and fire-escape, but is always ready for use, and the simplicity of construction renders it comparatively inexpensive.

What I claim is—

1. In a fire-escape, the combination, with a rail secured to the side of the building, of an upright supporting-frame carrying an endless ladder and having connected therewith a trolley or traveler mounted on said rail, said supporting-frame comprising longitudinal or upright members, and cross-pieces connecting said longitudinal members, substantially as indicated, the longitudinal members having

rearwardly-extending arms or brackets carrying rollers in contact with the building, and said longitudinal members inclosing the side pieces of the endless ladder on three sides, thereby preventing the swaying of the ladder in either direction, substantially as set forth.

2. In a fire-escape, the combination, with a rail secured to the side of the building, of an upright supporting-frame carrying an endless ladder and having connected therewith a trolley or traveler mounted on said rail, said supporting-frame comprising longitudinal or upright members, and cross-pieces connecting said longitudinal members, substantially as indicated, a crank for communicating motion to said ladder, and suitable mechanism for preventing a return movement of said ladder, substantially as set forth.

In testimony whereof I sign this specification, in the presence of two witnesses, this 18th day of November, 1891.

WILLIAM F. LOYD.
